UNITED STATES PATENT OFFICE.

GEORGE PRIFOLD, OF LINWOOD, PENNSYLVANIA, ASSIGNOR, BY MESNE ASSIGNMENTS,
TO UNITED ROOFING & MANUFACTURING COMPANY (DEPARTMENT OF BARRETT
MANUFACTURING COMPANY), OF WILMINGTON, DELAWARE, A CORPORATION OF
DELAWARE.

BLOCK-PRINTING MACHINE.

1,193,422.

Specification of Letters Patent.

Patented Aug. 1, 1916.

Application filed April 26, 1915. Serial No. 23,906.

To all whom it may concern:

Be it known that I, GEORGE PRIFOLD, a citizen of the United States, and a resident of Linwood, county of Delaware, State of 5 Pennsylvania, have invented certain Improvements in Block-Printing Machines, of which the following is a specification.

My invention relates to certain improvements in machines for printing oil cloth, 10 linoleum, and other materials, by the use of blocks which are mounted on reciprocating carriers. In this type of machine the material is moved forward intermittently and the printing blocks make the impression 15 during the dwell of the feeding mechanism.

The object of the invention is to provide means for automatically regulating the movement of the several block carriers so that bordered rugs, and like objects, can be 20 printed.

My improved mechanism provides for holding certain of the printing blocks out of action while a given portion of the fabric to be printed passes said blocks, and by this 25 means any particular design, such as a bordered rug, can be printed and the several color blocks belonging to certain portions of the rug will be allowed to make the impression while the other blocks will be held out 30 of action.

In the accompanying drawings:—Figure 1, is a side view of sufficient of a block printing machine to illustrate my invention; Fig. 2, is an enlarged side view of a portion of Fig. 1, showing the mechanism more in detail; Fig. 3, is a sectional plan view on the line *a—a*; Fig. 4, is a sectional perspective view of a portion of Fig. 2; Fig. 5, is a diagrammatic sectional view showing 40 the relation of the lugs of the chains to the pins on the latches; Fig. 6, is a view illustrating a modification of my invention; and Fig. 7, is a diagrammatic view of a rug.

Referring to the drawings, 1 is the frame 45 of a block printing machine, in the present instance having wheels 2 mounted on rails 3 of the usual type, but the frame may be mounted on a foundation when it is not desired to move the machine laterally.

4, 4^a, 4^b, 4^c and 4^d are the block carriers, in the present instance. Each block carrier consists of two uprights 5, which are adapted to slide in ways in the frame 1, and a cross member 6, which carries the blocks 7.

On each upright of each block carrier are 55 rollers 8, which are engaged by a cam 10 on the cam shaft 9 of the usual form. This shaft is driven from a longitudinal shaft 11 by a worm and worm gear.

12, 13 are the inking carriages, which are 60 reciprocated under the blocks and supply coloring material to the said blocks, while they are in the raised position.

13 is the feeding chain or band which passes around a wheel 14 and intermittent 65 motion is imparted to this band equal to the width of the printing block. Sufficient time is allowed for the cams 10 to actuate a block to make an impression.

Mounted on a shaft 15, which extends 70 from one side of the machine to the other at each carrier, are latches 16 having projecting portions 17 which engage projections 18 on the carrier and, when these latches are in engagement, as illustrated in Figs. 2 and 4, 75 the block is held out of action. It will be noticed that each cam 10 has a raised portion 10^a which lifts the carrier, at each revolution of the cam shaft 9, above the normal position. This allows the latches to be 80 inserted and withdrawn. When the latches support the carrier, as in Fig. 2, the weight of the carrier holds the latches in engagement. These latches have weights 19 which tend to throw the latches into engagement 85 with the carriers.

In order to automatically withdraw the latches from engagement with the carriers, I provide three endless chains 20, 20^a and 20^b which pass around a sprocket wheel 21 at 90 one end of the machine driven from the motive power of the machine in any suitable manner. On the chain 20 are lugs 22 and on the chain 20^a are lugs 22^a, and on the chain 20^b are lugs 22^b. The lugs 22 are of a greater 95 height than the lugs 22^a and the lugs 22^a are of a greater height than the lugs 22^b. On the latches at one side of the machine, or on an arm on the shaft 15, are pins 23 with which the several lugs engage. For instance, when it is desired to actuate a latch by the lugs 22, the pin 23 is extended to be in the path 91 the lug 22 and is of a sufficient height to clear the lugs 22^a and 22^b. If it is desired 100 that the lugs 22^a engage the pins, then the pins are of such a length as to clear the lugs 22 and of such a height as to clear the lugs 105

22^b, but if the pins are to be engaged by the lugs 22^b on the chain 20^c then the pins are short and are arranged at such a height as to be in the path of the lugs 22^b. The pins 5 on the latches are preferably made detachable, but they may be formed integral with the latches, or may be mounted on arms carried by the latch shafts.

The chains are of the detachable link type 10 and the lugs are on detachable links, so that they can be placed at any point on the chain, according to the size of the rug which it is desired to print and according to the number of colors. The chains are mounted on 15 sprocket wheels 21 on a shaft 24 and on this shaft is a gear wheel 25 which meshes with an intermediate wheel 26 which, in turn, meshes with a wheel 27 on the shaft 14^a on which the wheels 14 are mounted, so that 20 the chains, as well as the mechanism for the fabric, move intermittently and actuate the latches only when the parts are in the elevated position.

In some instances, I may use a single 25 chain, as in Fig. 6. This chain is indicated at 20^c and has lugs 22^c. These lugs can be located at different points on the chain and may be of different heights, while the pins 23^c can be of different lengths and arranged 30 at different heights so as to be in the path of different lugs and, consequently, act in the same manner as the three chains illustrated in Fig. 3.

The operation is as follows:—If a rug is 35 to be printed in two colors and in three sections, it will require six printing blocks, two for each section, and it will be necessary to arrange the lugs on the chains so that, as the fabric is intermittently fed through the 40 machine, certain of the blocks will be held out of action while others are printing. For instance, if a certain block makes an impression on the section *x*, Fig. 7, and an adjoining block has the design of the section *y* 45 and the next block the design of the section *z*, then these two blocks are held out of action while the printed portion *x* of the fabric is passing thereunder. The next block after *z* will be an impression of another color of 50 the design *x*, while the blocks having the impressions which print the sections *x* and *z* are held out of action during the time the section *y* is passing thereunder. The same is 55 the case when the impression *z* is made and, by arranging the lugs on the chain according to the number of sections of a rug to be printed and the number of colors to be printed on each section, I am enabled to auto-

matically hold any of the printing blocks out of action while certain parts of the fabric are passing thereunder. 60

When a rug of a greater or less length than that described, or having a larger or smaller number of colors, is to be printed, the lugs on the chains and the pins on the 65 latches are arranged accordingly. The chains may be arranged on both sides of the frame or at any point desired, according to the type of the machine to which the invention is applied. 70

I claim:—

1. The combination in a block printing machine of the horizontal type in which the material is intermittently moved forward over a bed, of a series of reciprocating carriers; printing blocks thereon; cams for raising the carriers; shafts on which the cams are mounted and means for driving the shafts; a pivoted latch arranged to engage each carrier when in the raised position; an endless chain; means for driving said chain; and a lug on the chain arranged to actuate a given latch at a certain time so as to release the carrier controlled by the latch and to allow its block to make an impression. 80

2. The combination in a block printing machine of the horizontal type, of a frame; a series of block carriers mounted on the frame; blocks on each carrier; a transverse 90 shaft in line with each carrier; a cam on each shaft for raising the carrier; a latch for holding the carrier in the elevated position and out of action; a pin on each latch; a series of endless chains; lugs on each 95 chain for engaging the pins of certain of the latches; and means for driving the chains in unison, the lugs releasing certain of the latches at predetermined points so as to allow certain blocks to make an impression. 100

3. The combination in a block printing machine, of a frame; a series of block carriers; a printing block on each carrier; means for reciprocating each block carrier; a weighted latch arranged to engage each 105 carrier and to hold it out of engagement; a series of longitudinally arranged endless chains; means for driving the chains; lugs on each chain, the lugs of one chain differing in height from those of the other chains; 110 pins varying in length so that certain of the pins will project into the path of certain lugs, whereby certain latches are actuated by certain pins; and means for intermittently feeding a fabric through the machine. 115

GEORGE PRIFOLD.
